(57) **CLAIM**

The ornamental design for a pickleball scoreboard, as shown and described.

DESCRIPTION

FIG. 1 is a front perspective view of a pickleball scoreboard showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a front right perspective view thereof in an environment of use; and,

FIG. 9 is a front perspective exploded view thereof in an environment of use.

The line shadings on the front face, rear face and indicator tile faces depict flat surfaces. The lines shadings on the scoreboard edge pieces and indicator tile corners depict curved surfaces. The broken lines shown in the drawings depict portions of the article that forms no part of the claimed design.
